(57) **CLAIM**

The ornamental design for a 5-in-1 payment module, as shown and described.

DESCRIPTION

FIG. 1 is a perspective view of a 5-in-1 payment module;

FIG. 2 is a front elevational view thereof;

FIG. 3 is a rear elevational view thereof;

FIG. 4 is a top plan view thereof;

FIG. 5 is a bottom plan view thereof; and,

FIG. 6 is a left side elevational view thereof, a right side elevational view thereof being an mirror image of the left side elevational view.

The broken lines showing of portions of the 5-in-1 payment module are for the environmental purposes only and form no parts of the claimed design.
